BRAKE FOR WINDING DRUMS

Richard E. Kline, Los Angeles, Calif., assignor,
by mesne assignments, to Oil Well Supply Com-
pany, Pittsburgh, Pa., a corporation of New
Jersey

Application May 21, 1929, Serial No. 364,769

5 Claims. (Cl. 188—77)

This invention has to do generally with brake devices, and relates more particularly to drum brakes especially adapted for use on winding drums for hoists, draw-works, oil drilling equipment, or the like.

The brake structure embodied in the invention is designed primarily with the view of providing for winding drums, and other devices including the combination of a rotatable drum and a brake band around the drum, a highly effective means for tensioning the brake band about the drum arranged in a manner such as to apply a portion of the band as a brake shoe. A further object of my invention is to permit maximum brake area of the band to be utilized.

The invention is characterized primarily by the particular manner in which the band is applied to the drum in effecting the braking action, this manner being such that the band not only is brought to bear tightly against the drum but, in addition, to be tensioned in the direction of rotation of the drum in such a way that the drum itself aids in tensioning the band. The band is applied to the drum in such a way that its bearing surface or lining is subjected to even wear; and as a provision for preventing unnecessary wear or dragging when not in use, the band is maintained out of engagement with the drum when the brake idles.

In order to accomplish effective brake action in the manner described, I have provided at the movable or free end of the band, the other end of the band being normally held stationary, a toggle connection with suitable actuating means. As a result of the action of the toggle, the band not only is drawn circumferentially about the drum, but the free end of the band is urged against the drum with sufficient force to cause said free end to be frictionally held by the drum, the latter, by virtue of its rotation, drawing the band tightly about itself. The particular construction and operation of the invention will be understood most readily and clearly from the following detailed description, reference being had throughout the description to the annexed drawings, in which:

Fig. 1 is a front elevation of a conventionally illustrated drum equipped with the present brake device;

Fig. 2 is an enlarged left end elevation of Fig. 1, the brake being shown in released position;

Fig. 3 is a view similar to Fig. 2 showing the brake applied to the drum;

Fig. 4 is an enlarged fragmentary view of a band anchor post; and

Fig. 5 is a part elevational and a part sectional view taken on the broken line 5—5 of Fig. 3.

In the preferred embodiment of my invention and as shown in the drawings, the brake means are shown in duplicate, although it will be understood that a single brake means may be applied to numerous types of drums other than the one shown.

In the drawings, a horizontally disposed winding drum 10 is employed. This drum is supported by means of a suitable framework, the framework including uprights 11 inter-connected by means of the cross member 11a. Trunnions 12 of the drum are journaled in bearings 13 mounted on the uprights, and the drum is adapted to be rotated by suitable drive means, for instance, the conventionally illustrated gear drive 14. Drum 10 is provided with enlarged cylindrical ends or brake flanges 10a, each constituting a brake drum and provided with brake bands 15.

As shown in Fig. 2, the brake band 15 has an integral lining 15a and its end 16 is pivotally anchored by means of a vertically adjustable post 17. The free end 18 of the band is free to move circumferentially about the drum and is connected to the brake operating lever 19 through the toggle mechanism, generally indicated at 20. The band is yieldably supported at an intermediate point 21 from the frame cross member 11a by means of the spring suspension 22. This suspension device embodies a strip 23 suspended from said cross member, a tube 24 carried by the strip, and through which the shank of a hook 25 extends. Tube 24 carries a spring 26, and 27 is a vertically movable washer in the tube resting on the upper end of the spring to enable the spring to yieldably support hook 25 and, therefore, the brake band. It will be apparent that, with the brake released as in Fig. 2, the band is raised from a resting position on the brake-drum or flange by means of the device 22, thereby preventing undue wear of the lining 15a. As will later be seen, when the toggle device 20 is in released position, there is no appreciable bearing of the brake bands against the drum around its lower periphery.

As previously mentioned, the fixed end 16 of the band is pivotally anchored to the upper end of post 17. As illustrated the joint therebetween embodies a horizontal pin 28 releasably held by set screw 29 in the enlarged head 17a of the post, the center of the band being cut away to receive said head portion and looped to form eyes through which pin 28 extends. The lower end of the post

is contained within a vertical sleeve 30, the latter having an annular flange 30a on its lower end disposed within an opening 31 formed in the under face of a block 31a. The sleeve is held in the block 5 against vertical displacement, and the latter in turn is secured to the platform or floor F by means of bolts 32. The post is threaded through a nut 33, integral with the upper end of the sleeve, and is held in vertically adjusted position by means of a 10 lock nut 33a. Thus, by having the post adjustable as described, the free end 16 of the band may be positioned as desired relative to the toggle 20, thereby providing for regulating the thrust of the toggle in urging the band radially against 15 the brake-drum.

The brake operating lever 19 as illustrated is integral with a horizontally extending crank shaft 19a, the latter extending substantially parallel with the axis A of the drum and preferably near 20 the base of the sleeves 30. As particularly shown by Fig. 1, the crank shaft extends the length of the drum 10, and, as will later be seen, serves to simultaneously actuate the brakes by tensioning the brake bands on each of the brake flanges 10a. 25 This shaft is journaled at its respective ends in saddle boxes 35 bolted to the floor F, and has crank arms 18b, one pair designed for cooperation with each of the toggles 20. Each pair of crank arms comprises one element of the toggle, 30 an offset pivot in the form of a pin 36 being carried by each pair of crank arms to constitute a toggle joint.

A plate 37 is fastened on the free end of the band 15 and is shaped on each side to provide a 35 pair of oppositely disposed bosses 37a drilled to receive pin 38. A link 39 is pivotally connected to plate 37, the arm 39a of the link terminating in bosses 39b drilled to receive the pivot pin 38. The link is also pivotally connected to the offset crank 40 pin 36 by means of a removable strap 40 extending around said pin and secured to the link by bolts 41.

It will be seen that by anchoring the fixed end 45 of the brake band at a point P substantially in vertical tangential alignment with the drum, and with the free end of the band terminating at a point intermediate the bottom B of the drum and the point P of tangency of said fixed end, said free end, by positioning the crank shaft near the 50 collar or sleeve 30, may closely approach the fixed end. Thus, the band practically surrounds the drum with the advantage that maximum brake area is provided.

It is assumed the direction of rotation of the 55 drum is that indicated by arrow R and that the toggle, through lever 19, is moved from the position of Fig. 2 to that of Fig. 3. Because of the characteristics of the toggle action, the free end of the band is caused not only to move circumferentially relative to the drum in the direction of rotation thereof, but also to be urged radially inward against the drum with sufficient force to frictionally engage the drum. Obviously, the frictional engagement of the free end of the band with the drum serves to cause the band to be 60 tightly drawn throughout its extent into engagement with the drum, and against the tension of the suspension device 22, by virtue of the rotational force of the drum. In addition, one component of the thrust imparted by the toggle is tangential to the drum. By thus making use of the momentum of the drum in tensioning the 65 brake band, the latter obviously may be tensioned to a much greater degree than would be 70

possible by mere tangential thrust alone on the free end of the band.

As previously mentioned, the effect of the toggle in producing radial thrust of the band against the drum may be varied by vertically adjusting 80 post 17 and, therefore, end 16 of the band, the effect being that the position of the latter relative to the drum is changed, and that the position of link 39 is varied accordingly. Thus, assuming post 17 to be lowered, the free end of the band moves about the drum in the direction of arrow S and the link 39 is swung counter clockwise. It will be apparent that by actuating the toggle in this position, the radial thrust imparted to the band through said link is increased by virtue 85 of the adjustment and that the frictional engagement of the band with the drum is correspondingly increased, the result being that added rotational force of the drum is harnessed in tensioning the bands. By raising instead of lowering the post, added tangential thrust of the band by the toggle obviously is effected at the expense of its radial thrust. 90

Upon releasing the brake to such positions that the band extends loosely about the drum, the 100 intermediate portion of the former is raised from engagement with the drum by virtue of the action of spring device 22, thus preventing wear of the brake lining. The lower portion of the band is sufficiently released from engagement with the 105 drum to prevent dragging and unnecessary wear of the lining when the brake idles. 95

It will be understood that the drawings and description are to be considered merely as illustrative of and not restrictive on the broader 110 claims appended hereto, for various changes in design, structure and arrangement may be made without departing from the spirit and scope of said claims.

I claim:

1. A brake device comprising a rotatable brake drum, a brake band for the drum, anchoring means for one end of the band, said anchoring means being adjustable to permit shifting of the band circumferentially about the drum, and operating means joined to the free end of said band, said means comprising a link freely pivoted between the band and said operating means and arranged within the angle between the brake band and a line normal thereto at the pivot between the link and the band so that a pushing force on said link is transmitted to said band with radial and tangential components, and means for applying a pushing force to the link to tension the band around the drum. 115

2. In a device of the character described, the combination of a rotatable brake drum, a brake band surrounding said drum, anchoring means for one end of the brake band, said anchoring means being relatively stationary during actuation of the brake band, and operating means joined to the free end of said band comprising a pushing element pivoted to the brake band and arranged within the angle between the brake band and a line normal thereto at the pivot of the pushing element and the band to apply a pushing force having a component toward the brake drum, and means for pushing said element, said anchoring means being adjustable to permit shifting of the band circumferentially about the drum to vary 125 the angle of incidence of the pushing force. 130

3. In a device of the character described, the combination of a rotatable brake drum, a brake band surrounding said drum, operating means for the brake band, and a relatively stationary sup- 135

port for said operating means, one end of said 5
brake band being anchored to said support, said
operating means comprising a crank shaft rotat-
ably mounted on said support and a link connect-
ing a crank of the crank shaft and the free end of
said band, said link being arranged within the
angle between the brake band and a line normal
thereto at the pivot of the link and the band.

4. A brake device comprising a rotatable brake
10 drum, a brake band surrounding said drum, a
vertically adjustable post for anchoring one end
of the brake band, a spring for freeing the band
from said drum when the band is released and
operating means pivoted to the free end of said
15 band, said means comprising a crank shaft, a link
pivoted to a crank of the crank shaft and pivoted
to the free end of said band, said link being ar-
ranged within the angle between the brake band
and a line normal thereto at the pivot between

the link and the band, and means for rocking
said crank shaft.

5. In apparatus of the character described, a
horizontal rotatable drum, a brake band for said
drum, adjustable anchoring means for one end of
said band arranged in upward tangential align-
ment with the drum, a free end of the band
terminating at a point intermediate the bottom
of the drum and the point of tangency of said
fixed end, actuating means for said brake band
and a link pivoted freely between the free end
of said band and a moving part of said actuating
means within the angle between the brake band
and a line normal thereto at the pivot point of
the link and movable freely between said moving
part and said end of said band to transmit to
said band end a pushing force having radial and
tangential components.
